(57) **CLAIM**

The ornamental design for a sphygmomanometer, as shown and described.

DESCRIPTION

FIG. 1 is a front, bottom, and right side perspective view of a first embodiment of a sphygmomanometer, showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front, bottom, and right side perspective view of a second embodiment of a sphygmomanometer, showing our new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The dashed broken lines in the figures show portions of the sphygmomanometer that form no part of the claimed design. The dot-dashed broken lines in the figures represent boundaries and form no part of the claimed design.

1 Claim, 12 Drawing Sheets
